CLAIM

The ornamental design for a clothes dryer machine, as shown and described.

DESCRIPTION

1. Clothes dryer machine

1.1 is a perspective view of a clothes dryer machine showing our new design;

1.2 is a front elevation view thereof;

1.3 is a rear elevation view thereof;

1.4 is a left-side elevation view thereof;

1.5 is a right-side elevation view thereof;

1.6 is a top plan view thereof;

1.7 is a bottom plan view thereof; and

1.8 is another perspective view thereof, in a use condition. The broken lines in the drawing figures are included for the purpose of illustrating environment and form no part of the claimed design.

1 Claim, 8 Drawing Sheets(56)
